J. H. LEVIS, JR

TELEPHONE SYSTEM

Filed Sept. 16. 1925

UNITED STATES PATENT OFFICE.

JOHN H. LEVIS, JR., OF ROCHESTER, NEW YORK, ASSIGNOR TO THE STROMBERG-CARLSON TELEPHONE MANUFACTURING COMPANY, OF ROCHESTER, NEW YORK, A CORPORATION OF NEW YORK.

TELEPHONE SYSTEM.

Application filed September 16, 1925. Serial No. 56,758.

This invention relates to telephone systems and more particularly to small exchange systems, which cooperate with a main telephone system.

5 In private branch exchanges, such as are used in offices and apartment houses, there are certain conditions, which must be met in order to give efficient service, when such branch exchanges function with main automatic exchanges.

Among the greatest difficulties encountered in operating a private branch exchange in connection with a main automatic exchange is that known as false preliminary 15 impulses. It is well known that in an automatic exchange the automatic switches are operated by a series of line interruption varying in number in accordance with the desired connection; it, therefore, becomes 20 necessary when a private branch exchange is connected to a main automatic exchange to obviate all line interruptions, except those originating from the dial sender at the private branch exchange.

25 Also when private branch exchanges, which were designed to connect with manual telephone exchanges, are to be used in connection with automatic exchanges, the cord circuits of said private branch exchanges must be reorganized for use in 30 the new system.

The main feature of the present invention resides in the novel arrangement of circuits for a private branch exchange, which 35 will function with a main automatic exchange without introducing false preliminary impulses into the system.

Another feature of the invention resides 40 in the designs of cord circuits for a private branch exchange, which are adaptable for use in connection with manual or automatic telephone systems.

Other features of the invention will appear from the detailed description and appended claims.

In the drawing there is indicated at the left, a private branch exchange telephone line of which there are a plurality. In the center of the drawing there is indicated diagrammatically, one of a plurality of cord circuits of which there are several, while at the top of the sheet there is diagram-

matically indicated a dial sender, and an operator's telephone set, which may be connected to any of the cord circuits. At the right of the drawing there is indicated a second private branch exchange line, while at the extreme lower left and at the extreme lower right, there is indicated a portion of a trunk circuit, which connects with a main 60 automatic telephone system.

It is believed that the invention will best be understood by describing the method of completing the different types of calls which may be extended through the system. 65

Call from P. B. X. line to another P. B. X. line.

When the subscriber at A initiates a call by removing his receiver from its switchhook, the line relay 5 is energized over the two sides of the calling line in series and through the contacts of the cut-off relay 6, to grounded battery, in the well-known manner. The energization of the line relay 5 lights the line lamp 7 to signal the operator that a line is calling. The operator then inserts the plug P of an idle cord circuit in to the jack J of the calling line. At this time the various keys are in the condition indicated on the drawing, so that the sleeve relay 8 is energized from grounded battery, its winding, contacts 9 of the thru dialling key, sleeve contacts of the plug P and jack J, winding of the cut-off relay 6 to ground. 70 75 80

Sleeve relay 8 and the cut-off relay 6 are energized in this circuit. The sleeve relay on operation connects the answering supervisory relay 10 to the answering end of the cord circuit for the purpose of providing 85 supervisory means in the form of a lamp 11. The connection of the supervisory relay 10 to the answering end of the cord circuit, results in its energization and at its armature and back contact opens the lighting circuit of lamp 11, which is otherwise completed at one point at the lower front contact and armature of relay 8. The energization of the cut-off relay 6 disconnects the line relay 5 from the calling line, thereby 90 permitting it to deenergize and extinguish the line lamp 7. The operator thereupon connects her telephone set (not shown), by means of conductors 12 and 13 and the

contacts 14 and 15 of the listening key to the answering end of the cord circuit, which is connected to the calling telephone line. On inquiring for and receiving the designation of the wanted line, such as B, the operator inserts the calling plug P' of the cord circuit into the jack J' of the wanted line. This results in the energization of the sleeve relay 16 in a circuit traceable from grounded battery, its winding, conductor 17, contacts 18 of the thru dialling key, conductor 19, sleeve contacts of the plug P' and jack J' , winding of the cut-off relay 20 to ground. The cut-off relay 20 is energized at this time to disconnect the line relay 21 from the called line, which prevents the lighting of the line lamp 22 when the called party answers. The sleeve relay 16 on energization connects the calling supervisory relay 23 to the calling end of the cord, which permits supervision on this end of the cord, by means of the supervisory lamp 24.

The operator thereupon depresses the ringing key and closes a circuit through the contacts 25 and 26, from the source of ringing current over the calling end of the cord circuit and the called line with the substation call signal included in series therewith, the subscriber at substation B on noting this signal removes his receiver from its switch-hook, which completes a direct current path from ground and grounded battery through the two windings of the calling supervisory relay 23 and the contacts of the sleeve relay 16 through the two sides of the calling end of the cord circuit and the called line in series. This energizes relay 23 and at its lower armature and front contact, closes a circuit for actuating the relay 27, which circuit is completed at the lowermost front contact and armature of relay 16. Relay 27 when energized in this circuit, at its upper front contact and armature, closes a locking circuit for itself, independent of the control of relay 23. Relay 27 is ineffective at this time.

At the close of the conversation, when the calling subscriber replaces his receiver on its switch-hook, the answering supervisory relay 10, has its operating circuit opened and thereupon deenergizes. This results in the lighting of the supervisory lamp 11, from battery, through this lamp, back contact and armature of the relay 10, lowermost front contact and armature of relay 8 to ground. When the called subscriber replaces his receiver on the switch-hook, the calling supervisory relay 23 has its operating circuit opened and also deenergizes. This results in the lighting of the calling supervisory lamp from grounded battery through this lamp, lower back contact and armature of relay 23, front contact and armature of relay 16 to ground.

The operator on noting that these lamps are both lighted, removes the plugs P and P' from the jacks with which they have been in engagement. This results in the deenergization of the sleeve relays 8 and 16, which restores the equipment to its normal condition. It will be noted that a ring-back key is shown in connection with the answering end of the cord circuit and is provided for use whenever the subscriber asks the P. B. X. operator to ring a special number and then call him back when the called party is reached. Under such a condition, it is not necessary to remove the answering plug P from the jack of the calling line, but when the called party is found, the ring-back key is operated to apply signaling current to the calling line, as a result of which the subscriber removes his receiver from the switch-hook and proceeds with the call.

Call from main automatic exchange to private branch exchange line.

When a subscriber, whose telephone line terminates at an automatic exchange (not shown), desires to extend a telephone connection to a line such as that designated B, he removes his receiver from its switch-hook and operates the dial sender associated with his line (also not shown), to transmit several series of impulses corresponding to the designation of the private branch exchange line. In response to these series of impulses automatic switches (not shown) extend the calling line to the trunk circuit, the conductors of which are designated 28. In accordance with the operation of this automatic equipment, after the seizure of the trunk 28, ringing current is applied over the two sides of the trunk 28 and the contacts of jack J^2 through the left hand winding of the relay 29. This relay is so designed that it responds to this alternating current and attracts its armature to light the trunk lamp 30. On noting that lamp 30 is lighted the operator inserts the plug P of an idle cord circuit into the jack J^2 and since the sleeve of the jack J^2 has no potential thereon, the sleeve relay 8 is not energized, with the result that the answering supervisory relay 10 is not operated as in the case of a local call.

The insertion of the plug P into the trunk jack, however, completes a circuit from the upper side of the trunk 28 through the tip contacts of the jack J^2 and the plug P , through the contacts of the ring-back key, upper armature and back contact of the sleeve relay 8, contacts 31 of the thru dial key, winding of the relay 32, inner back contact and armature of relay 8, contacts 33 of the last mentioned key, over the lower side of the answering cord and the lower side of the trunk 28 to the automatic exchange. At that exchange, the circuit is completed

through grounded battery, so that the relay 32 is operated for a purpose to be described.

The operator thereupon depresses her listening key to connect her telephone set 5 through contacts 14 and 15 of this key to the mentioned cord circuit and inquires the number of the wanted line over the portion of the connection thus far completed. On ascertaining that the wanted line is that indicated at B, the operator inserts the plug P' into the jack J', and then depresses the ringing key to apply ringing current to the wanted line. When the called party responds by removing his receiver from its 15 switch-hook, the supervisory relay 23 is operated in the manner already described. On the operation of this relay, the relay 27 is energized from grounded battery, its winding, inner front contact and armature 20 of relay 23, front contact and armature of relay 16 to ground. Under this condition of the circuits, when the called party terminates the connection, by replacing his receiver on its switch-hook, the supervisory 25 relay 23 deenergizes and thereby completes a circuit from ground, armature and back contact of relay 23, the supervisory lamp 24, to grounded battery and in multiple therewith through the armature and front 30 contact of relay 27, conductor 34, lower armature and front contact of relay 32 and thence through the answering supervisory lamp 11 to grounded battery. On noting that the supervisory lamps 11 and 35 24 are lighted, the operator removes plugs P and P' from the jacks with which they have been in engagement, with the result that the cord circuit equipment reverts to its normal condition.

40 *Call from private branch exchange to automatic main.*

Let it be assumed that a subscriber, such as A, at a private branch exchange desires 45 to obtain a connection to a subscriber whose line terminates at a main automatic exchange. The calling subscriber initiates a call in the manner previously described, by removing his receiver from its switch-hook, which results in the lighting of the line 50 lamp 7. The operator then inserts the plug P of an idle cord circuit into the jack J of the calling line, which results in the operation of the sleeve relay 8 and in consequence the operation of the supervisory 55 relay 10, in the manner already described. The operator then depresses the listening key to connect her telephone set to the calling line. It will be noted that there may 60 be a multiple connection from the operator's telephone set to the calling end of the cord circuit through the dial key, which connection includes the dial sender. The operator then asks for the number of the wanted line 65 and when she learns that this line terminates

at a main exchange, inserts the plug P' of the calling end of her cord circuit into the jack of a trunk leading to the main automatic exchange. Either of the trunk circuits, partially shown, in the drawing, may be used for this purpose. Let it be assumed that the plug P' is inserted into the jack J' of one of these trunks. The operator presses the dial key and waits until a dialling tone is heard in her head set, which tone is an indication that the equipment at the automatic exchange is in readiness to receive the directive impulses from the dial sender, shown at the upper part of the drawing.

The operator then actuates the dial sender mechanism, diagrammatically indicated in the drawing, to send several series of impulses corresponding to the designation of the wanted line. In accordance with the well known operation of this sender mechanism, the impulse springs 35 thereof, are intermittently opened and closed, depending on the adjustment of the sender. During the operation of the springs, shunt springs 36 are closed to short-circuit the operator's telephone set, so that no electrical disturbances resulting from the opening and closing of impulse spring 35 will be heard by the operator. The impulses, due to the opening of the impulse spring 35 are transmitted to the switches at the main exchange, over trunk conductor 37 through the tip contacts of the jack J' and plug P', conductor 38, contacts 39 of the dial key, thence through the impulse spring 35, and shunt springs 36, contacts 40 of the dial key, conductor 41, ring contacts of the plug P' and jack J' and thence over the conductor 42 to the automatic switches at the main exchange. It will be noted that this impulse circuit has included 100 in series therewith, the impedance 45, which serves at this stage to maintain the switches of the connection operated.

In this connection, since there is no potential present on the sleeve of the jack J', the sleeve relay 16 is not operated and consequently the calling supervisory relay 23 remains inactive. However, in order to provide supervision during this call, the relay 46 is bridged across the talking connection as follows: conductor 37, tip contacts of the jack J' and plug P', through the normal contacts of the ringing key and the dial key, conductor 47, armature and back contact of relay 16, conductor 48, normal contacts 49 of the thru dial key, conductor 50, winding of relay 46, conductor 51, inner back contact and armature of relay 16, conductor 52, normal contacts 53 of the dial key, normal contacts of the ringing key, conductor 54, ring contacts of the plug P' and jack J' to conductor 42 of the selected trunk.

At the termination of the conversation, when the calling subscriber at A replaces his receiver on its switch-hook, the answer-

ing supervisory relay 10 deenergizes, but the sleeve relay 8 remains operated, consequently the supervisory relay 11 is lighted from grounded battery, through this lamp, back contact and armature of relay 10, lower front contact and armature of relay 8 to ground. The calling supervisory lamp 24 is also lighted from grounded battery conductor 55, armature and front contact of relay 46 and thence in multiple with the circuit last described, back contact and armature of relay 10, front contact and armature of relay 8 to ground.

The operator on noting that these lamps are lighted, removes the plugs P and P' from the jacks with which they have been in engagement, which causes the cord circuit equipment to return to its normal condition.

It will be understood that the wipe out key included in series with coil 45, permits the operator to erase a connection in case an error in dialling is made by the operator.

Thru dialling operation.

Under certain conditions, such as at night, when there is no operator at the switchboard, it is frequently desirable in the case of certain subscribers to provide continuous service. In order to take care of this contingency, private branch exchange lines desiring such service are provided with dial senders, such as that diagrammatically indicated at 56. Whenever it is desired to provide a subscriber with such service the plug P of a cord circuit is inserted into the jack J of such a line and the plug P' is connected to an idle trunk, while the thru dial key is operated. It should be noted that the innermost sets of contacts on this key are of the make-before-break or continuity type. In other words, there is a continuity of circuits through these contacts, while the key is being adjusted, from one position to another. With this thru dial key operated, even with the plug P in engagement with jack J, the relays 8, 10 and 32 remain inactive. Consequently, the circuit including the dial sender is connected around the condensers 57 and 58. A portion of this dialling circuit may, therefore, be traceable from the tip of the plug P' through the normal contacts of the ringing and dial keys, conductor 47, armature and back contact of relay 16, conductor 48, contacts 59 of the thru dial key, upper back contact and armature of relay 8, the contacts of the ring-back key, tip of the plug P and the jack J, through the dial sender 56, and thence over the lower side of the calling line, ring contacts of the jack J and the plug P, normal contacts of the ring-back key, contacts 60 of the thru dial key, relay 61, conductor 51, inner back contact and armature of relay 16, conductor 52, normal contacts

of the dial and ringing keys, conductor 54, to the ring contact of the plug P'.

When night service is furnished, the battery supply to the lamp 24 is interrupted by a key or other suitable switch, but in the event that the battery source is still connected to the cord circuit, this supervisory lamp is lighted on disconnection, in a circuit from grounded battery through this lamp, conductor 55, back contact and armature of relay 61, contact 62 of the thru dial key to ground.

What I claim is:

1. In a telephone system, a plurality of telephone lines, a trunk line, means including a plurality of cord circuits for interconnecting said telephone lines, a disconnect signal at each end of each cord circuit and controlled thereover, an operator's telephone set and an impulse sender common to said cord circuits, a listening key for connecting said operator's telephone set to one of said cord circuits, a second key for connecting said operator's telephone set and impulse sender in parallel to one end of said cord circuit, means including a relay associated with said cord circuit energized over said trunk line and one end of said cord circuit for placing the control of the operation of both of the disconnect signals of said cord circuit at one end thereof.

2. In a telephone system, telephone lines, a trunk line, a cord circuit for interconnecting said lines, a supervisory relay at each end of said cord circuit, a disconnect signal controlled by each relay, a control relay in each end of said cord circuit, and means including said trunk line for operating the control relay of the end of the cord circuit connected to said trunk, and means including said last mentioned relay for placing a disconnect signal under the control of the supervisory relay of the other end of said cord circuit.

3. In a telephone system, a plurality of telephone lines, a trunk, cord circuits for connecting any telephone line with any other telephone line and with said trunk, an answering supervisory lamp and a calling supervisory lamp associated with each cord circuit, a supervisory relay associated with, but normally disconnected from the calling end of each cord circuit, a sleeve relay functioning to connect said supervisory relay to the calling end of its associated cord circuit, an energizing circuit for said sleeve relay completed over the telephone line to which the calling end of said cord circuit is connected, a third relay having an energizing circuit completed by the operation of said supervisory relay and said sleeve relay, a circuit for the calling supervisory lamp controlled by said supervisory relay and by said sleeve relay, and a circuit for the answering supervisory lamp completed at contacts of

all of said relays while the answering end of the cord circuit is connected to said trunk.

4. In a telephone system, a plurality of telephone lines, a trunk, cord circuits for connecting any telephone line with any other telephone line and with said trunk, an answering supervisory lamp and a calling supervisory lamp associated with each cord circuit, a supervisory relay associated with, but normally disconnected from the calling end of each cord circuit, a sleeve relay functioning to connect said supervisory relay to the calling end of its associated cord circuit, an energizing circuit for said sleeve relay completed over the telephone line to which the calling end of said cord circuit is connected, a third relay having an energizing circuit completed by the operation of said supervisory relay and said sleeve relay, a locking circuit for said third relay independent of said supervisory relay, a circuit including the calling supervisory lamp controlled by said supervisory relay and by said sleeve relay, and a circuit for the answering supervisory lamp controlled by all of said relays.

5. In a telephone system, a plurality of telephone lines, a trunk line, means including a cord circuit for connecting a telephone line with any other telephone line and with said trunk, a supervisory signal at each end of said cord circuit, a relay arranged to be operated when the answering end of its cord circuit is connected to said trunk line, a supervisory relay associated with, but normally disconnected from the calling end of said cord circuit, a sleeve relay arranged when the calling end of said cord circuit is extended to a telephone line for connecting said supervisory relay to said cord circuit, a

fourth relay arranged to be operated by the simultaneous operation of the supervisory relay and the sleeve relay, a circuit for the calling supervisory lamp jointly controlled by said supervisory relay and said sleeve relay, and a circuit for the answering supervisory lamp jointly controlled by all of said relays.

6. In a telephone system, a plurality of telephone lines, at least one of which is provided with an impulse sender, a trunk, cord circuits for connecting any telephone line to any other telephone line and with said trunk, each cord circuit having its ends conductively separated but inductively connected together by means of condensers, a manual key at each cord circuit for short-circuiting the condensers thereof, whereby an impulse sender can send impulses over its telephone line and through the cord circuit and trunk connected thereto, a supervisory relay at each end of each cord circuit, but normally disconnected therefrom, a sleeve relay for each end of each cord circuit arranged to be operated in a circuit including said cord circuit and the telephone line to which it is connected, each sleeve relay being arranged to be inactive when the end of the cord circuit with which it is associated is connected to said trunk, each sleeve relay serving to connect its associated supervisory relay with said cord circuit, the circuit of each sleeve relay being controlled at said manual key, and a supervisory signal controlled by each supervisory relay.

In witness whereof, I hereunto subscribe my name this 11 day of September, A. D. 1925.

JOHN H. LEVIS, JR.
